UNITED STATES PATENT OFFICE.

DATUS C. SMITH, OF JACKSON, MICHIGAN.

FIELD-FENCING.

No. 905,942.

Specification of Letters Patent.

Patented Dec. 8, 1908.

Application filed February 13, 1908. Serial No. 415,707.

To all whom it may concern:

Be it known that I, DATUS C. SMITH, a citizen of the United States, residing at Jackson, in the county of Jackson and State 5 of Michigan, have invented certain new and useful Improvements in Field-Fencing; and I do hereby declare the following to be a full, clear, and exact description of the invention, such as will enable others skilled in 10 the art to which it appertains to make and use the same.

This invention relates to manufactured wire fencing intended for fields or pastures and more particularly such widths of the 15 same as are designed to be used in connection with supplementary barb wires strung above the fencing when it is erected on the fence posts.

The purpose of my improvement is to enhance the value of such fencing by incorporating in the manufactured product convenient means for binding such barb wires together and to the fabric fencing and thereby increasing the efficiency of the completed 25 fence.

Woven wire or fabric fencing, of which there are several styles or constructions in the class above referred to, is manufactured in widths ranging commonly from twenty- 30 six to forty-five inches, the same being respectively less, as a general rule, than the heights of various field fences made therefrom and used for restraining different species of live stock. Such fencing is used 35 almost universally in connection with barb wires placed on top or running above the fabric and completing the height of the fence. Occasionally such fencing is used alone for small pastures for sheep and swine, 40 but probably ninety percentum of fabric fencing in the widths mentioned is used in connection with barb wires as stated. This form of fence, that is a combination of fabric fencing and complementary barb wires, employing 45 approximately seventy-five per cent. of all fabric fencing made, is adopted for the sake of economy, since it diminishes the width of the more expensive manufactured product, while yet bringing the fence to the 50 requisite height. A fence constructed wholly of woven wire or fabric fencing cannot be permanently kept in good condition at a less height than about sixty inches from the ground. Otherwise it is ridden down and 55 injured by horses leaning over its smooth top to browse outside the pasture.

As a general rule, the barb wires are run wholly independently of the main fencing; that is they are not attached to the latter in any way. The result is that the barb wires, 60 being unsupported between the fence posts, are more flexible than they should be, and moreover, on account of the tendency of the stock to crowd these wires apart, they must necessarily be placed closer together to obtain 65 the same restraining effect than if bound together and to the fabric fencing. This closer spacing of the barb wires adds to the cost of the fence, yet does not, at best, give 70 the stability desired.

The expedient of binding the barb wires to the subjacent fencing is rarely resorted to, because it has hitherto entailed the trouble and expense of preparing or buying 75 separate stays or wire sections and attaching them to the fencing preliminary to connecting them to the complementary fence wires. The cost of purchasing such special stays, handling and transporting, including manufacturers' and dealers' profits; or, 80 where home-made binders are provided, the trouble and expense of procuring the wire, especially the more desirable hard-drawn wire which is seldom carried by dealers, and straightening and cutting the same into 85 accounting for profits and labor from the lengths; with all the separate handlings and original coil of plain wire to the time when the separate binders are attached on the fencing, are sufficient considerations to 90 dissuade the average farmer from the undertaking.

In view of the foregoing, I have devised the improved product of manufacture herein set forth, which consists of a woven wire or 95 fabric fencing made with flexible binders as a component part thereof; such binders being spaced at suitable intervals and extending from the top of the fencing for sufficient lengths for attachment to the complementary barb wires which are to be subsequently strung above the fencing when erected on the fence posts. The important 100 economical result is thereby attained of eliminating all the various expenses of production and handling, intermediary profits, and labor of installation, incident to the use of detached wire binders; besides further advantages presently to be considered.

The flexible binders of the new product 110 above mentioned may consist of extensions or continuations of some of the stays or

cross-wires that go to make up the fencing. This would be particularly so with that large class of fabric fencing in which each stay consists of a single wire extending across 5 and joined to all the strands. Where the stays consist of short wire sections connecting adjacent strands, the binders may advantageously be applied as separate sections joined to the top strand coincidently with 10 and virtually constituting continuations of the stays. Or the binders may be independently attached to the top strand of the fencing.

The fencing is or may be supplied in the 15 usual form of rolls, with its flexible binders folded back upon the fabric to make compact bundles for storage, shipment and transfer. They may also, in some cases, be simply folded upon the top of the roll, especially where the binders are short. When 20 the fencing is unrolled in the field and erected upon the fence posts, with its ready-made binders thus already attached, spaced at regular and proper intervals, in position 25 for applying to the subsequently strung barb wires, it is merely necessary to straighten up the binders and join them to the barb wires by the usual method of coiling or twisting; though the binders may be otherwise 30 joined to the barb wires, as by means of small clamps for example; in this case the flexibility required being only at the joint of the binder to the fabric.

Referring to the accompanying drawings, 35 which form a part of this specification: Figure 1 shows diagrammatically a section of one style of fabric fencing provided with flexible binders in accordance with my invention. Fig. 2 shows in perspective a roll 40 of said fencing, with the flexible binders folded back upon the fabric and within the roll. Fig. 3 shows in elevation an erected field fence made of the aforesaid fabric fencing and complementary barb wires, 45 which are bound together and to the fabric fencing by the said flexible binders; thus illustrating the use of my improvement. Figs. 4, 5, 6, 7 and 8 are fragmentary views, on a larger scale, of sections of several different 50 styles of fabric fencing made with said flexible binders attached in different ways.

a and *b* denote respectively the longitudinal strands and cross wires composing the manufactured fencing; *c* the flexible binders or binding wires made as a component part 55 of the fencing; *d* the barb wires which are strung above the erected fencing; and *e* the fence-posts.

The diagrammatic Figs. 1 to 3 may be 60 taken to represent any of various well known styles of fencing. For example, they may represent a fencing wherein the stays, each consisting of a single length of wire, extend across and are joined by coils, wraps or otherwise to all the strands; and in this case the

binders *c* preferably consist of extensions or continuations of some of the stays, at regular intervals of desirably three or more feet apart. In the manufacture of this style of fencing, these binders are or may be formed 70 by providing every third or other determined stay with an added length of wire. On the other hand, said Figs. 1 to 3 may represent a fencing wherein the individual stays, although practically continuous across the 75 strands, are composed of segments or separate pieces arranged end to end and respectively connecting adjacent strands; and in this case the binders *c*, consisting of other segments of the same sort added to some of the 80 stays and joined coincidently therewith to the top strand, may also be considered as virtually extensions or prolongations of the stays with which they are connected. As the fencing is made in the loom, these binders are or may be formed by providing at every third or other determined stay an independent feeding of a suitable length of wire.

The last described style of fencing, which 90 is in extensive use and a desirable form for the purposes of my invention, is represented more clearly in Fig. 4, showing a hinged binder or binding wire attached as a separate piece to the top strand, but secured with and 95 substantially as a unitary part of the stay. This may advantageously be done in the fence-making machine by simultaneously coiling around the top strand the extremities of the binder wire and the adjacent stay 100 wire, by means of the same coiling pin; the binder wire being desirably placed across the strands along side of the stay as the two extremities are thus attached, leaving the binder to be bent up above the top strand 105 afterward.

Fig. 5 shows another style of fencing, known commonly as woven-wire fencing, in which a hinged binder is attached as an independent piece to the top strand; while in 110 Fig. 8, showing a fencing having its stays joined by clamps to the strands, the binders are made by continuing or extending the upper portions of some of the stays.

Figs. 6 and 7 show wire fabric fencings 115 having electrically welded stays. In Fig. 6, the stay is prolonged above the fencing to provide the flexible binder; while in Fig. 7 the binder consists of a separate length of wire also electrically welded to the top strand. 120 In this case, the binder is shown attached so as to extend normally downward or across the fabric, instead of upward, being more conveniently formed in this manner during the manufacture of the fencing. Such a 125 binder would need to be bent upward when brought into use, as indicated by dotted lines.

As the manufactured fabric passes through or comes from the machine, ready to be 130

reeled into rolls or bundles, the extended binders (unless made as in Fig. 7) are bent downward and folded back upon the fabric, as previously mentioned and as indicated in Fig. 2, making a compact bundle and avoiding the extra space that would be required for storage and shipment if the binder wires were allowed to extend from the end of the roll; while also avoiding the expensive extra width of machine that would be required to accommodate projecting binders. The mode of folding back the binders upon the fabric is immaterial, whether the binders be carried straight across or diagonally, provided a compact roll of usual height be provided. Or the binders may advantageously be drifted back substantially parallel with the top strand of the fencing and just below that strand. This may be and is preferably done automatically as the fencing is made in the loom or other machine. But where the binders are attached as separate pieces, it is more practicable to apply them already lying upon or across the strands, as previously mentioned in connection with the description of Fig. 4.

In the use of my improved fencing, after it is erected and the barb wires are strung on the posts in the usual manner, the flexible binders are straightened up and wound or coiled about the successive barb wires, from the bottom one up, as indicated in Fig. 4. While some wires are so flexible as to permit doing this by hand, as a rule it would be necessary or at least expedient to use some simple tool. The binder is simply given a compact turn or two around each of the barb wires, being deflected between the fence wires as it is carried around, as indicated in Fig. 4; which is permitted by the flexibility of the binder wire.

Considering the fence as a whole, inasmuch as a more efficient fence is obtained, the posts may naturally be placed further apart, which is an important economical consideration in view of the growing scarcity of timber. For erecting wire field fencing, the spacing between fence posts as recommended by manufacturers is from one to two rods according to circumstances. Where the posts are spaced at distances of about two rods, intermediate shorter or lighter posts are frequently resorted to in order to hold up the fabric fencing from swaying between the posts. This necessity is obviated by use of the flexible binders provided in my improved product.

Another valuable result from the use of

my improved fencing in connection with barb wire lies in affording much greater safety to the stock. As the barb wires are now arranged, that is without being bound together, whenever one of the barb wires breaks, as will sometimes happen, the longer end falls to the ground, and the stock, particularly horses, often get their feet engaged in it and are seriously injured. So serious is this objection that some farmers will not permit any barb wire to be used on their farms, even in connection with fabric fencing. But with the use of the binders provided in my improved fencing, whenever a barb wire breaks the end will be at most not over two or three feet in length and cannot drag on the ground and engage the feet of stock running along the fence. Also the broken wire will be held in place so there will not be a large breach in the fence through which stock may escape.

Such modifications as attaching the binders to a lower strand than the top strand of the fencing, or to the stays, are intended to be included within the scope of this invention.

I claim as my invention and desire to secure by Letters Patent:

1. As a new article, manufactured wire fencing provided with flexible binders made as a component part of such fencing and adapted for binding supplementary fence wires when the fencing is erected.

2. As a new article, manufactured wire fencing consisting of longitudinal strands and cross stays composed of wire segments or sections connecting respectively adjacent strands, and binders consisting of other segments added to some of the stays adapted to extend above the fencing when erected.

3. As a new article, manufactured wire fencing made with binders for attachment of supplementary fence wires, said binders adapted to lie folded upon the fencing but adapted to be lifted up to extend above the fencing when erected.

4. As a new article, a roll or bale of manufactured wire fencing having flexible binders for attachment of supplementary fence wires, said binders being arranged to avoid projection from the roll but adapted to be extended above the fencing when unrolled.

In testimony whereof I affix my signature, in presence of two witnesses.

DATUS C. SMITH.
